UNITED STATES PATENT OFFICE.

JOHN E. FERNEBORG, OF DENVER, COLORADO, ASSIGNOR OF ONE-HALF
TO CARL M. LINDQUIST, OF DENVER, COLORADO.

HAT-FASTENER.

SPECIFICATION forming part of Letters Patent No. 781,717, dated February 7, 1905.

Application filed April 8, 1904. Serial No. 202,148.

To all whom it may concern:

Be it known that I, JOHN E. FERNEBORG, a citizen of the United States of America, residing in the city and county of Denver and State of Colorado, have invented certain new and useful Improvements in Hat-Fasteners; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in hat-fasteners; and my object is to provide a device adapted to be permanently connected with the hat and capable of such adjustment that the hat may be fastened to the head of 20 the wearer or released, as may be desired. The device is of course intended for use in connection with ladies' hats, and it is intended to do away with the necessity or requirement for hat-pins.

25 My further object is to provide a device of this class which shall be simple in construction, economical in cost, reliable, durable, and efficient in use; and to these ends the invention consists of the features, arrangements, and combinations hereinafter described and claimed, all of which will be fully understood by reference to the accompanying drawings, in which is illustrated an embodiment thereof.

35 In the drawings, Figure 1 is a view of a hat with the crown partly broken away and showing my improved device applied. Fig. 2 shows the device applied, but on a larger scale, the greater portion of the hat being 40 broken away and the tubular parts of the device shown in section. Fig. 3 is a similar view on a smaller scale, but showing the device in elevation. Fig. 4 is a section taken through one extremity of the device and showing the adjacent fastening-plate. Fig. 5 is a detail view of one of the pivoted lever-like holding devices or claws. Fig. 6 is a fragmentary section of a modified form of the device.

The same reference characters indicate the 50 same parts in all the views.

Let A designate the crown of a hat, which may be of any suitable construction. To the opposite sides of the hat-crown and to the inner surface thereof are attached two plates B, 55 to which are secured the extremities of two tubular parts C, having threaded parts C', provided with right and left threads, respectively. These two parts C are connected by a sleeve C', whose extremities are interiorly 60 threaded to receive the right and left threads of the parts C, whereby the length of the device may be adjusted at will by simply turning the sleeve C'. Within the tubular device, composed of the tubes C, C', and C', is 65 located a coil-spring D, against the opposite extremities of which bear small pistons or stops E, mounted on rods F, whose outer extremities pass through openings formed in the plates B and through the fabric of the 70 hat-crown A, the exteriorly-protruding extremities of the rods having buttons G screwed thereon or otherwise secured thereto. The inner extremity of each rod F projects a short distance beyond the stop or piston E and enters the spring D, whose convolutions surround the inner protruding extremities of the rods in order to guide the latter. Between the extremities of each rod and protruding through slots H, formed in 75 the tube C, are cams F', formed by bending the rods, whereby the bent portions are made to protrude through the slots H of the tubes.

Pivotedly connected with each tube C at points I are the holding devices J, which are lever-like features having claws or hook-shaped holding extremities J', adapted to engage the hair of the wearer of the hat to which the device is applied. The pivoted claws or lever-like holding devices J pass through slots 80 H and H', formed in the opposite sides of the tubular parts C. On the opposite side of the pivot I from the claw J' is located an arm J'', having a bifurcated upper extremity J'', which straddles the cam or bend F' of the reciprocating rod, whereby as the rod is moved back and forth the holding device is actuated. The arrangement is such that the spring D is nor-

mally under tension and the outer inclines of the cams engage the bifurcated extremities of the holding devices, whereby the claws or holding devices are thrown to the position indicated in Figs. 2 and 3 of the drawings and at the left of Fig. 1.

Now if it be assumed that the parts are in the position shown in full lines in Fig. 2, which is the normal position, if it is desired to put the hat upon the head the user will press the buttons G inwardly to the dotted-line position in Fig. 2 of the drawings, whereby the claws or holding devices are thrown to the position indicated by dotted lines in the same figure, permitting the hat to be placed upon the head in the usual manner. Then by releasing the buttons the spring D forces the rods outwardly sufficiently to manipulate the holding devices and throw them to the locking or holding positions, whereby they are made to engage the hair of the wearer.

It is believed that this is a thoroughly practicable device and that when applied to a hat will prove far superior to the ordinary hat-pins.

In Fig. 6 I have shown a modified form of the invention whereby the lever-like holding device may be held in the released position or in a position to permit the removal of the hat from the head. To this end I have provided each rod F with a tooth or lateral projection F³, adapted to engage an oppositely-disposed stop C³, formed on each tube C. The tooth and the stop are so arranged that when the rod F is pushed inwardly a distance (indicated by the distance between the dotted-line position and the full-line position of the button G in Fig. 6) the tooth will engage the stop, whereby the holding device J is locked at the released position. In order to allow the holding device to resume its normal position, it is only necessary to pull downwardly on the rod sufficiently to allow the tooth F³ to pass the stop C³, when the spring D will return the rod to its normal position, whereby the holding device is made to engage the hair of the wearer of the hat. In order to permit the necessary downward movement of the rod C, the opening in the fabric of the hat through which the rod passes must be somewhat enlarged, as shown at A'.

Having thus described my invention, what I claim is—

1. In a hat-holder, the combination of a tubular device, a coil-spring located therein, rods having stops bearing against the spring, lever-like holding devices fulcrumed on the tubular device, the rods being provided with parts projecting beyond the line of their body portions and acting on the lever-like holding

devices to normally hold them in the holding position, the rods being capable of reciprocal movement whereby the holding devices may be thrown to the released position.

2. The combination of two plates adapted to be connected to the opposite sides of a hat-crown, two tubular parts rigidly connected with said plates and having their extremities remote from the plates provided with right and left screw-threads, a connecting-sleeve inferiorly threaded to engage the right and left threads of the two tubular parts, a coil-spring inclosed by the tubular parts, reciprocating rods provided with pistons engaging the extremities of the coil-spring, the said rods passing through the crown of the hat and their outer exposed extremities being provided with buttons, each rod having a bent portion which protrudes through a slot formed in the adjacent tubular part of the device, and holding devices pivoted on the respective tubular parts and having their outer extremities bifurcated to engage the bent parts of the rods for the purpose set forth.

3. In a hat-holder, the combination of a tubular device, a coil-spring located therein, rods having stops bearing against the spring, lever-like holding devices mounted on the tubular device, the rods being provided with parts projecting beyond the line of their body portions and acting on the lever-like holding devices to normally hold them in the holding position, the rods being capable of reciprocal movement whereby the holding devices may be thrown to the released position, and suitable means for locking the holding devices in the released position against the action of the spring.

4. In a hat-holder, the combination of a tubular device, a coil-spring located therein, rods having stops bearing against the spring, lever-like holding devices mounted on the tubular device, the rods being provided with parts projecting beyond the line of their body portions and acting on the lever-like holding devices to normally hold them in the holding position, the rods being capable of reciprocal movement whereby the holding devices may be thrown to the released position, and suitable means for locking the holding devices in the released position against the action of the spring, comprising a tooth formed on each rod and adapted to engage a stop on the tubular device, substantially as described.

In testimony whereof I affix my signature in presence of two witnesses.

JOHN E. FERNEBORG.
